ARTHUR PENTECOST, OF NEW YORK, N. Y., ASSIGNOR TO WALES ADDING MACHINE COMPANY, OF WILKES-BARRE, PENNSYLVANIA, A CORPORATION OF PENNSYLVANIA.

PAPER-CARRIAGE MECHANISM.

Application filed June 25, 1920. Serial No. 391,714.

To all whom it may concern:

Be it known that I, ARTHUR PENTECOST, a subject of the King of England, residing at New York city, New York County, New York, have invented new and useful Improvements in Paper-Carriage Mechanisms, of which the following is a specification.

More particularly, this invention is directed to improvements in return mechanisms for the paper carriages of calculating machines, whereby the paper carriage is mechanically restored, either to the beginning of a new line, or to another column in the same line which has passed the printing point.

One of the objects of this invention is to provide a carriage-returning mechanism wherein wear of the parts is materially reduced.

20 This is effected by arranging that the drive mechanism for returning the carriage to the beginning of a line shall be normally idle, and only brought into use at such times as the operator desires to shift the carriage.

25 Another object is to facilitate the ready engagement and disengagement of the separable members by means of which power is imparted to the carriage-return mechanism, to thereby reduce wear to a minimum and 30 render the mechanism more silent in operation.

35 This result is accomplished by effecting the engagement of the separable drive and driven members through positively operating means, and by arranging for their quick disconnection by tensioned means instantly effective upon the withdrawal of the positive means which causes the engagement of the separable members.

40 Furthermore, the separable members are each provided with spiral threads adapted to lead the members into mesh with each other, so that in the remote event that the engaging mechanism should only partially effect the engagement of the separable members, the latter will automatically become fully engaged, due to the lead of the intermeshing threads.

45 Another object of the invention is to prevent mismanipulation of the paper carriage-returning mechanism, to which end, the operator's key or lever does not directly control the means for effecting the engagement

of the separable members, and hence the operator may not either accidentally or intentionally maintain a partial engagement only of the separable members, which would result in an unpleasant chattering noise and injury to the parts. 55

Still another object is to effect the automatic disconnection of the power and the carriage-restoring mechanism at the point of complete restoration of the carriage to the beginning of a line, to thereby avoid injury to the mechanism, in case the operator should intentionally or unintentionally retain the operating key or lever in actuated position after the carriage has reached the limit of its return travel. 60

A further object is to enable the operator, 70 by the manipulation of a single key or lever to determine whether the carriage shall return to the beginning of a line, or shall return to any intermediate point at the will of the operator. 75

Still further objects are the provision of novel line space mechanism to automatically advance the paper as the carriage restores to the beginning of a line, such line spacing mechanism becoming operative when the carriage has but partly returned; and the provision of cushioning or shock-absorbing means to reduce the jar incident to the contact of the tabulating stops on the paper carriage with the arresting abutment, such cushioning means being of material advantage when the operator effects the disconnection of the clutch members prior to the complete restoration of the carriage to the beginning of a line, as when additional amounts are to be printed in columns which have previously fed past the printing point. 85 90

These and other objects and advantages will be hereinafter more fully referred to and particularly pointed out in the claims. 95

In the accompanying drawings, Figure 1 is a side view of a portion of the well-known Wales motor-driven calculating machine, showing the left hand end of the paper carriage, to which one embodiment of my invention is applied; 100

Figure 2 is a rear view, parts being omitted, the carriage-returning mechanism being in its normal idle position;

Figure 3 is a detail top plan view of the 105 carriage-controlled means to effect the auto-

matic disconnection of the separable members, in the act of effecting such disconnection;

Figure 4 is a top plan view, partly in section, illustrating one means to control the separable members; the mechanism being in normal idle position;

Figure 5 is a detail sectional plan of the separable members and operating parts in idle position;

Figure 6 is a top plan view, partly in section, showing the positions assumed by the controlling mechanism for the separable mechanism when tripped;

Figure 7 is a detail sectional plan of the separable members and operating parts in active position; and

Figure 8 is a side view of a Wales machine illustrating the dual means through which the engaging mechanism for the separable members is caused to operate.

The invention is applicable to traveling paper carriages adapted to be shifted in letter or column spacing direction, and returnable toward the beginning of a line. I have illustrated one embodiment of my invention, applied to the well-known Wales motor-driven calculating machine, a more comprehensive understanding of which may be had by an inspection of U. S. patents to Wales 797,032, August 15, 1905; McFarland 842,232, January 29, 1907; Wilgus, 1,150,916, August 24, 1915, and Pentecost, 1,223,419, April 24, 1917, for example.

Such machines include a base 969, Figure 8, supporting side frames between which the calculating and printing mechanisms are mounted. A main drive shaft 200 is mounted in the side frames (not shown). A case 1065 encloses the operating parts. A carriage bracket 2067 is supported by and extends transversely across the rear end of the machine, the bracket including ways or rails 2067^m on which travels a carriage slide 2065. End plates 2010 secured to the carriage slide 2065 support a platen axle 2004 on which is mounted the platen 2094. A ribbon case or housing 1810 containing the ribbon mechanism, is removably mounted between the platen and the types (not shown).

The paper carriage is drawn from right to left in the usual manner, by a spring drum 2068, (Figs. 2 and 8), the tape 2099 of which is connected to the carriage slide 2065 at any suitable point.

Tabulating stops 1 on a tabulating bar 2 extending between and journaled at its opposite ends in the end plates 2010, are adapted to successively contact a flexible abutment 2024^e (Fig. 2) to arrest the carriage at various columnar positions along its path of travel. The abutment forms part of a carriage escapement whereby the carriage may be automatically stepped from

right to left to bring successive columns to the printing point. Preferably, as shown in Fig. 8, the tabulating bar is provided with pintles 2^a journaled in the end frames 2010.

The stops 1 may be disengaged from their abutment 2024^e to permit the carriage to travel from column to column, by tilting the tabulating bar 2, as illustrated in the U. S. patent to Pentecost 1,223,419, April 24, 1917, above referred to, or in Schuppe, 1,308,117, July 1, 1919, and the stops 1 may be adjustable along the bar 2, as illustrated in such patents. In the present instance, the abutment 2024^e is the pawl (Fig. 2) of an escapement, such pawl being pivoted at 3 on a sliding plate 2024^s spanning the space between the rails 2067^m and guided on studs 2055^e projecting from the respective rails 2067^m. A disabling spring 4 attached to one arm of the pawl tends to shift the tooth of the pawl out of the path of the tabulating stops 1. Contact of a tabulating stop 1 with the tooth of the pawl or flexible abutment 2024^e turns the latter in a clockwise direction (looking from the rear) 90 against the tension of the disabling spring 4, until the pawl is arrested by the contact of its arm 2024^w, with a stop stud 5 on the sliding plate 2024^s, at which time, the tooth of the pawl lies squarely across the path of the tabulating stop 1 to arrest farther travel of the carriage under the influence of the spring drum 2068.

It will be understood that, in the particular class of machines in connection with which I have illustrated this embodiment of my invention, the keys 117 (Fig. 8) corresponding to the amount to be registered and listed, in an adding operation, are depressed after which the main drive shaft 200 is actuated to effect the registration and listing of the amount.

By utilizing the main drive shaft 200 to control the column spacing or tabulating action of the paper carriage, amounts can be more quickly listed in a horizontal line, or in other words, cross tabulated.

The main drive shaft 200 is turned on its forward stroke by a handle (not shown) or by a motor 1690. A drive rack 1668 (Fig. 8) actuated by the motor, meshes with a toothed segment 267^b fast on the main drive shaft 200. Clutch mechanism, (not shown) controlled by a starting key 966^b, connects and automatically disconnects the motor and drive rack 1668, so that by depressing the starting key, the motor drives the main shaft 200 on its forward stroke and is then automatically disconnected therefrom to enable the main drive spring 285 connected to the main drive shaft to return the shaft 200 and connected parts to their normal positions of rest.

For a more complete understanding of this mechanism, reference is made to U. S. 130

patents to Kuntzler, 1,151,803, August 31, 1915; Wilgus, 1,150,916, August 24, 1915, and Hunter and Kuntzler, 1,225,960, May 15, 1917.

5 The control of the carriage tabulating mechanism from the main drive shaft, may be conveniently effected as follows:

Links 214 connect cranks 212 on the main drive shaft 200 with a swinging frame 10 common to the Wales machine, comprising radius bars 323 journaled on a cross shaft 300 and joined by parallel cross rods or braces 302 and 303, the rear ends of the links 214 being connected to the cross rod 303, to enable the main drive shaft 200 to swing the frame. The usual Wales thrust bar 2026, whose forward end is connected to the cross rod 302, extends rearwardly through the back of the machine, and carries 20 a yoke 6 embracing the wrist 7 (Figs. 1, 2 and 8) of a crank arm 8 mounted on a crank shaft 9 journaled in ears 10 in a bracket 11 secured to the back of the machine. A strut 12 depending from the sliding 25 escapement plate 2024^g, rests on the wrist 13 of a second crank arm 14 on the crank shaft 9, the arm 14 lying at an angle to the arm 8. The strut 12 is yieldingly held in contact with the wrist 13 by a flexible link or spring 15 which connects the 30 sliding plate 2024^g with the crank arm 14.

The main drive shaft 200, on its forward stroke, swings the cross bar 302 forwardly and advances the thrust bar 2026 with its 35 yoke 6 to turn the crank shaft 9 and lower the crank arm 14. The sliding plate 2024^g carrying the pawl 2024^e follows the crank arm 14 downwardly by gravity, assisted by the spring 15, to withdraw the tooth of the 40 pawl abutment 2024^e from the path of the tabulating stop 1 at that time in contact with the pawl.

In addition to the yielding abutment 2024^e, the sliding plate 2024^g carries a fixed 45 pallet 16 (Fig. 2), the left hand face of which (looking from the rear) lies substantially in line with the contact face of the tooth of the pawl, and just above the path of travel of the tabulating stops 1, 50 when the parts are in their normal positions.

As the sliding escapement plate 2024^g descends, and prior to the disengagement of the yielding pawl 2024^e from the adjacent 55 tabulating stop 1, the plate interposes the fixed pallet 16 into the path of the adjacent stop 1 to retain the carriage against advancing in column spacing direction during the forward stroke of the main drive 60 shaft.

As soon as the pawl or abutment 2024^e escapes the adjacent tabulating stop 1, the spring 4 connected to the pawl, rocks the latter in a counter-clockwise direction (looking 65 from the rear) to displace the tooth of

the pawl relatively to the adjacent tabulating stop, the carriage at that time being held stationary by the fixed pallet 16.

The printing mechanism operates near the end of the forward stroke of the main drive shaft 200, after which, the carriage may be fed or allowed to escape to the next column in the following manner. The main drive shaft 200, on its return stroke, operates through the links 214 and the swinging 70 frame 323, 302, 303 to force the thrust bar 2026 and its yoke 6 rearwardly, thereby turning the crank shaft 9 to raise arm 14 and the sliding escapement plate 2024^g. As the escapement plate ascends, it displaces 75 the fixed pallet 16 from in front of the adjacent tabulating stop 1, and the spring 4 having rocked the pawl or flexible abutment 2024^e, so that its tooth no longer lies adjacent the fixed pallet 16, the tabulating 80 stop 1 escapes past the flexible abutment and the spring drum 2068 is free to draw the carriage in column spacing direction.

However, the continued travel of the sliding escapement plate 2024^g immediately introduces the end of the tooth of the flexible abutment 2024^e into the path of the succeeding tabulating stop 1, which, on the farther travel of the carriage, contacts the abutment and turns it in clockwise direction (viewing Fig. 2) until the arm 2024^m of the abutment strikes the stop stud 5, at which time the paper carriage is arrested with the succeeding column positioned 90 at the printing line.

The impact of the successive tabulating stops 1 against the flexible abutment 2024^e under the influence of the spring drum 2068 and the consequent arrest of the comparatively heavy paper carriage, would impart 100 a considerable jar and shock to the machine, to reduce which I preferably permit the tabulating bar 2 to have a slight amount of endwise play in the end plates 2010, the extent of which play is limited by the contact 110 of the ends of the bar against the end frames 2010. One end of a cushioning device, as a spring 17 (Fig. 2), is attached to the tabulating bar 2 intermediate its ends, the opposite end of the cushioning device 115 being secured to the adjacent end plate 2010, to normally hold the tabulating bar 2 at the extreme right hand limit of its travel (as viewed in Fig. 2). The carriage, in 120 traveling in column spacing direction (from left to right looking from the rear, as in Fig. 2) will impinge its stop 1 against the flexible abutment 2024^e, whereupon a slight relative movement will occur between, the tabulating bar 2 and the paper carriage 125 against the tension of the cushioning device 17 which will thus absorb the greater portion of the shock and jar incident to the arrest of the carriage, and then reassert itself against the influence of the spring 130

drum 2068 to restore the tabulating bar 2 and carriage to their normal relative positions.

Successive operations of the main drive shaft 200 will automatically feed the carriage step by step in column spacing direction, until it reaches the end of the line.

It then becomes necessary to return the carriage part way or entirely to its opposite limit of travel, depending upon whether a new line is to be commenced intermediate the left and right hand margins, or at the left hand margin.

To automatically return the carriage from any point which it may have reached in its column spacing travel, to a preceding point, or to the beginning of a new line, I provide carriage-returning mechanism to connect the motor 1690, which operates the main drive shaft 200, with the carriage.

Heretofore, in many instances the carriage-restoring mechanism has been connected with the continuously running motor to be driven thereby as long as the motor remains operative, and is therefore, subjected to a vast amount of unnecessary wear, as the carriage-return mechanism is brought into use intermittently, that is, only when it is desired to restore the carriage towards the beginning of a line.

My invention is designed to provide a novel and simple means to eliminate this unnecessary and useless wear and thereby greatly prolong the life of the mechanism and reduce its liability to get out of order and the necessity of replacing worn parts.

Therefore, I extend the armature-carrying shaft 18 (Figs. 1 and 2) of the motor rearwardly, and apply thereto a worm 19, forming one of two coacting separable members. The extended motor shaft 18 with its worm 19, projects over or within a housing or other suitable support 20. A support or plate 21 is slidably mounted in the housing in any convenient manner, as by a pin and slot connection 22, for movement transversely to the axis of the motor shaft. The lower end of a carriage return shaft 23 is provided with a step bearing 24 (Fig. 2) in the shiftable support 21 and carries a worm wheel 25 adapted to releasably mesh with the worm 19 on the motor shaft 18, and constituting the remaining separable member. The carriage return shaft 23 extends upwardly through a guide bracket 26 mounted on the rear of the calculating machine, and carries a gear 27 in constant mesh with a rack 28 supported by brackets 29 projecting from the carriage slide 2065.

A spring 30 (Figs. 5 and 7) connected to the housing 20 and to the shiftable plate 21, respectively, tends to hold the worm wheel 25 apart from and out of mesh with its worm 19. This spring constitutes a disen-

gaging means for the separable members 19 and 25.

It will be noted that normally, the worm wheel 25 is out of mesh with its worm 19, and as a consequence, the carriage return mechanism is not at such times, driven by the motor. Hence unnecessary wear is eliminated. Of course, the carriage return shaft 23 rotates idly as the carriage shifts from column to column, due to the constant engagement of the carriage rack 28 with the pinion 26.

Engagement of the worm wheel 25 with its worm 19 will enable the rotatable motor shaft 18 to turn the carriage return shaft 23 and through the gear 27 and rack 28, to drive the carriage to the right (the left, viewing Figs. 2, 4 and 6) towards the beginning of a line.

To effect such connection of the separable members 19 and 25, I provide an engaging element in the form of a cam 31 fast near the lower end of a control shaft 32, arranged substantially parallel with the motor shaft 18, the lower end of which control shaft 32 passes through a slot 33 (Figs. 5 and 7) in the sliding plate 21 and has a step bearing in the bottom of the housing 20. The control shaft 32 with the pin 22, serves to guide the shiftable plate 21 in its travel. The face of the cam 31 is adapted to wipe against a roller stud or toe 34 mounted on the sliding plate 21, and the cam face may terminate in an abrupt rise 35 which, by contact with the toe 34, arrests the travel of the cam in one direction.

The control shaft 32 extends upwardly through the guide bracket 26 which serves as a bearing therefor, and at its upper end, carries a trip arm 36 fast thereon, adapted to enter the path of travel of a tappet 37 mounted at or near one end of the carriage return rack 28.

Rotation of the control shaft 32 in clockwise direction (Fig. 5) wipes the cam 31 against the toe 34 to crowd the sliding plate 21 to the right (in said figure) against the tension of the disengaging spring 30, to shift the carriage return shaft 23, and engage the worm wheel 25 with the worm 19. The spiral thread on the worm 19, when the worm wheel 25 is partially meshed therewith, tends to lead the worm wheel into complete mesh, and it will be observed that the engaging element 31 acts to positively enforce the connection of the separable members 19 and 25.

The engaging element 31 might be shifted to effective position by other means, but in the present instance, I have shown a manually-operable means to initiate the operation of mechanism by which the engagement of the separable members 19 and 25 is effected.

Such manually-operable means is so arranged that the operator has only an indirect control of the engaging element 31 when the latter is to be shifted to effective position, in order to prevent accidental or intentional mismanipulation of the engaging element 31, whereby the lands of the spiral teeth might be brought to and held in contact, to the injury and possible breakage of the parts.

Furthermore, it is sometimes advantageous in the interest of saving time, to provide dual means whereby to initiate the operation of the carriage-return mechanism, one of which means can be located at or near the front of the machine, another being located at the rear of the machine adjacent the paper carriage where it will be convenient for operation as the operator completes the removal of a ledger sheet from the machine, after having made the desired entries thereon. By this arrangement, the carriage-return mechanism can be restoring the carriage to the beginning of a line, while the operator is filing the ledger sheet away, and selecting the next ledger sheet to be inserted in the paper carriage.

In ledger posting, it is customary to list at the left hand the old balance, shift the carriage to bring the next column to the printing line, list the debits if any, tabulate the carriage to the next column, and list the credits, after which the carriage shifts to the next column, in which the new balance is printed. In banking, several columns may be assigned to the debit items, which may be the amounts of individual checks, and in case a greater number of checks are to be listed than there are columns appropriated therefor, it is necessary to restore the carriage from the last debit column partway towards the beginning of the line to bring the first of the debit columns to the printing point, whereby to start a new line of debit entries.

With my invention, the operator can at will, initiate or interrupt the return travel of the carriage at any point in its path of travel, to accommodate the carriage to the exigencies of the particular work being done.

Pursuant to these ends, I provide an operable member, as a link 38 (Figs. 1, 4, 6 and 8) extending along the base 969 of the machine from front to rear, the rear end of the link projecting beyond the base and being slotted, as at 39, (Fig. 1) to accommodate the outer end of an actuating lever 40, the hub 40^a of which is loosely journaled on the control shaft 32, adjacent an arm 41, which may take the form of a segmental plate, fast on the control shaft 32. A check stud 42 on the arm 41 limits the travel of the actuating lever 40 towards or over the arm, to

arrest the actuating lever in its home position. The travel of the arm 41 is, in turn, controlled by the arc of travel of the engaging element 31.

A dog 43 pivotally mounted at 44 on the actuating lever 40, releasably engages a keeper 45 carried by the arm 41, whereby to enable the actuating lever 40 to turn the control shaft 32, in one direction only, and cause the engaging element 31 to effect the engagement of the driven separable member 75 with the separable driving member 19.

A spring 46 connected at its opposite ends to the dog 43 and to an anchor post 47 on the actuating lever 40, tends to enforce the engagement of the dog with its keeper 45.

A driving means, as a spring 48, is utilized to shift the actuating lever 40, and consequently, the engaging element 31 to effective position, such drive spring 48 being conveniently mounted on the rear end of the operable member or link 38 between the outer end of the actuating lever 40 and a cross stud 49 mounted in the operable member. The drive spring 48, when energized, is superior to the disengaging spring 30 and the friction caused by the contact of the cam 31 with the toe 34.

A key or hand lever 50 (Fig. 8) in the form of a bell crank is pivoted at 51 within the case 1065, one arm of the hand lever 95 being articulated with the operable member or trip link 38, the opposite arm of the lever conveniently projecting forwardly through a slot 52 in the front end of the case and being equipped with a handle for operation.

A second handle 53 (Figs. 1, 2 and 8) pivoted intermediate its ends at 54, to the machine and loosely connected, preferably by the cross stud 49, to the operable member or trip link 38, extends upwardly to a point 105 adjacent the left hand side of the carriage to facilitate the operation of the engaging member 31 by the operator just as he removes the work from the machine. The handle or key 50 or 53 constitutes the actuating means for the operable member or trip link 38.

The indirect control of the engaging element 31 by the operable member or trip link 38 whereby mismanipulation is prevented, is arranged as follows.

Rocking the hand lever 50 downwardly, or the handle 53 forwardly, thrusts the operable member or trip link 38 rearwardly relatively to the actuating lever 40, the operable member or trip link shifting relatively to the actuating lever due to its slotted connection 39 therewith. The cross stud 49 in the operable member or trip link 38 tends to press the drive spring 48 against the actuating lever 40, and obviously, if no restraint is provided, as soon as sufficient power is stored in the drive spring 48 to overcome the dis-

engaging spring 30 and the inertia and friction of the parts, the drive spring 48 would rock the actuating lever 40 to operate the engaging element 31.

- 5 To prevent such quasi-control of the engaging element 31 by the operable member or trip link 38, I preferably releasably lock the actuating lever 40 in its normal idle position by means of a catch or detainer 55 (Figs. 4 and 6) pivoted at 56, to the actuating lever 40, and extending forwardly through a guide slot 57 (Fig. 2) in the base 969 of the machine to take over a keeper 58 mounted on the base 969. A spring 59 connected at its opposite ends to the catch 55 and to the actuating lever 40, respectively, tends to maintain the catch in yielding engagement with its keeper 58.

The catch 55 restrains the actuating lever 40 against shifting the engaging element 31 to effective position as the operable member 38 travels rearwardly, and as a result, power is gradually stored in the drive spring 48 until it is sufficiently strong to snap the engaging element 31 smartly to its effective position, to engage the separable members 19 and 25.

As this stage is reached, a trip finger 60 conveniently mounted on the shifting operable member or trip link 38 to travel therewith, contacts a cam face 61 on the catch or detainer 55 to disengage the latter from its keeper 58, and thereby free the actuating lever 40 and its connected parts to the action of the drive spring 48.

The drive spring thereupon rocks the actuating lever 40 independently of the operable member or trip link 38, towards the outer end of the slot 39 formed therein, and through the releasable dog 43 and keeper 45, turns the arm 41 and control shaft 32 to wipe the engaging element 31 along the toe 34 and thereby shift the slide 21 to bring the member or worm wheel 25 into mesh with the drive worm 19, against the tension of the disengaging spring 30. Contact of the abrupt cam rise 35 against the toe 34 arrests and maintains the parts in effective position.

50 Engagement of the separable members 19 and 25, assuming the motor 1690 to be running, enables the motor to drive the carriage return shaft 23 and the gear 27 in mesh with the rack 28, to restore the carriage towards the beginning of a line.

It will be noted that the foregoing arrangement absolutely precludes the possibility of mismanipulation of the engaging element 31 by the operator.

60 The actuating lever 40 normally lies near the outer end of the slot 39 in the operating member or trip link 38. The trip link, when operated by either of the handles 50 or 53, shifts its slot 39 rearwardly relatively to the actuating lever, but immedi-

ately after the trip finger 60 releases the catch 55, the drive spring 48 snaps the actuating lever 40 rearwardly towards the outer end of the slot 39 in the operable member or trip link 38, in meshing the separable members, and thereby places the actuating lever 40 under the control of the operator directly through the levers 50 and 53 and the trip link 38. This enables the operator at will to swing the engaging element 31 to its ineffective position, by the contact of the actuating lever 40 with the check stud 42 on the arm 41, and thereby permits the disabling spring 30 to effect the disengagement of the separable members 80 and interrupt the return travel of the carriage at any point. Such interruption may occur at any time, and by the manipulation of either handle, though the operator will find the hand lever 50 more conveniently situated for this purpose.

When the operator desires to return the carriage partway only to the beginning of a line, he will rock the hand lever 50 downwardly, and the drive spring 48 will effect the engagement of the separable members, whereupon the carriage will start its return travel. The operator, by watching the progress of the columns past the printing point, can determine when the column in 95 which he wishes to print the next item, has returned to the printing point, at which time he will raise the hand lever 50, thereby advancing the trip link 38, which draws the actuating lever 40 forwardly to withdraw 100 the engaging element 31 to its ineffective position and thereby free the sliding plate 21 for operation by the disengaging spring 30 to disconnect the separable members 19 and 25. The flexible abutment 2024^e yields 105 against the tension of its spring 4 in a counter-clockwise direction (viewed from the rear) to permit the passage of the successive tabulating stops 1 as the carriage returns towards the beginning of a line.

The suspension of the transmission of power to the carriage on its return, may occur when none of the tabulating stops 1 are closely adjacent the left side (viewed from the rear) of the tooth of the abutment, but the carriage feed spring 2068 will draw the carriage in column-spacing direction until arrested by contact of the nearest tabulating stop 1 with the abutment 2024^e.

110 The cam face 61 on the detainer or catch 55, with which the trip finger 60 cooperates to release the catch, is of sufficient extent to maintain contact with the keeper 58 when the catch is released, so as to guide the catch back to its effective position upon the return of the actuating lever 40 to normal, under the control of the operator through the trip link 38, or automatically as herein-after set forth.

The trip finger 60 is withdrawn from its proximity to the cam face 61 as the operable member or trip link 38 advances to its normal position, whereby to enable the catch 55 to engage its keeper 58 under the influence of its spring 59.

Rocking the handle lever 53 rearwardly from its actuated position will effect the interruption of the carriage return travel in 10 the same manner as does the hand lever 50.

However, it is customary in ledger posting work for the operator to pull the lever 53 forwardly to start the carriage on its return, and while the carriage is returning 15 to the beginning of a line, the operator files away the previously printed card and selects the next card to be inserted about the platen.

To effect the automatic disconnection of 20 the motor 1690 and the carriage-returning means, when the carriage reaches the beginning of a line, I provide the carriage-return rack 28 with the tappet 37 located at or near the right hand end of the rack (looking from the rear, as in Figs. 1, 2, 4 and 6). As the carriage arrives at the beginning of a line, the tappet 37 collides with the trip arm 36 fast on the upper end of the control shaft 32, to turn the shaft in 25 a counter-clockwise direction and thereby swing the engaging element 31 to its idle position, to free the shiftable separable member 25 to the action of the disengaging means or spring 30.

35 The consequent separation of the separable members 25, 19, interrupts the transmission of power from the motor to the drive gear 27, and permits the carriage feed spring 2068 to reassert itself and draw 40 the carriage in column spacing direction until the first active tabulating stop 1 contacts the abutment 2024°.

It might be possible for the operator, either intentionally or unintentionally, to interfere with the automatic shifting of the disengaging element 31 to its ineffective position, by continuing to hold the handle 50 depressed or the handle 53 forward after the carriage reaches the beginning of a line, 45 which would maintain the operable member or trip link 38 in its rearward position.

To prevent such mismanipulation, an automatically operated means is provided for releasing the actuating lever 40 from control 50 of the engaging element. Thus, a releasing arm 62 having a lip 63 thereon, is fast to the upper end of a hollow shaft or sleeve 64 (Figs. 1 and 2) encircling the upper part of the control shaft 32. The releasing arm 60 extends into the path of return of the tappet 37 which is adapted to collide therewith just prior to its contact with the trip arm 36, and turn the sleeve in counter-clockwise direction. The lower end of the hollow 65 shaft or sleeve 64 rests loosely upon the hub

40* (see Fig. 2) of the actuating lever 40, which hub, in turn, rests loosely upon and is supported by the hub 41* of the segmental plate or arm 41 secured to the control shaft 32. A releasing cam 65 fast on the hollow 70 shaft or sleeve 64, extends over the plate or arm 41 and lies adjacent a releasing stud 66 on the dog 43, which connects the actuating lever 40 with the control shaft 32 through its engagement with the keeper 45 on the 75 plate 41.

The anchor post 47 mounted in the plate 41, passes through a slot 67 in the release cam 65 to define the throw of the release cam, and a spring 68 connected to the cam and to the anchor post normally holds the cam 65 at one end of its travel, with the releasing arm 62 in the path of the tappet 37, and near one end of such path.

In case the operator, after actuating the 80 handle 50 or 53, releases control of the same by removing his hand therefrom, the carriage on its return, will cause its tappet 37 to contact the release arm 62 to turn the hollow 90 shaft 64 and the release cam 65 counter-clockwise, against the tension of the spring 68, thereby causing the cam to wipe over the releasing stud 66 on the dog 43 to disengage the dog from its keeper 45.

The carriage immediately thereafter 95 brings its tappet 37 into contact with the trip arm 36 to turn the latter and the control shaft 32, and thereby shift the engaging element 31 to its ineffective position.

The tappet 37, in turning the trip arm 36, continues to turn the release arm 62, and the spring 68 acting as a flexible link between the actuating lever 40 and the release cam 65 will, in the absence of restraint imposed by the operator, cause the return of the actuating lever 40, and catch 55, to normal position, the actuating lever being pressed against its check stud 42 so that the dog 43 lies in position to take over its keeper 110 45, although disengaged therefrom. The actuating lever, on its return, will restore the operating member or trip link 38 and the levers 50 and 53 to normal.

As soon as the power is disconnected from 115 the carriage-return mechanism, the carriage with its rack 28, moves slightly towards the right (in Figs. 3, 4 and 6) as the first active tabulating stop contacts the flexible abutment 2024°, thereby withdrawing the tappet 120 37 on the rack 28 from proximity to the trip arm 36, and release arm 62, which latter, under the influence of the tensioned spring 68, turns in a clockwise direction, to its normal position, the spring also swinging the release cam 65 to idle position to permit the dog 43 to reengage its keeper 45.

Assume, however, that the operator maintains control of the operable member or trip link 38 to prevent its return, together with 130

the actuating lever 40, catch 55 and dog 43, to normal position, when the carriage arrives at the beginning of a line. The tappet 37 on the carriage, after first actuating the 5 release arm 62 to cast off the dog 43 from its keeper 45, will, in its farther travel, during which it acts upon the trip arm 36, merely turn the release cam 65 a little further in its counter-clockwise travel and further tension spring 68.

The arm 41, being disconnected from the actuating lever 40, will swing in a counter-clockwise direction under the pressure of the tappet against the trip arm 36, relatively to 15 the dog 43 to shift the keeper 45 away from the dog, as the engaging element 31 is restored to idle position. Hence, the operator cannot prevent the disconnection of the carriage-returning mechanism from the motor 20 when the carriage reaches the beginning of a line, as the connection between the actuating lever 40, trip link 38 and hand lever 50 or 53, with the arm 41 is completely broken.

Upon the advance of the carriage in column spacing direction at the beginning of a line to take up the slight space between the first tabulating stop 1 and the flexible abutment 2024^a, as above explained, the spring 68 restores the release arm 62 and release 30 cam 65 to normal, thereby freeing the dog 43 to the action of its spring 46, but the keeper 45 having shifted beyond the dog 43, the operator, in order to reestablish his indirect control of the engaging element 31, is 35 forced to manually restore the hand lever 50 or 53 to normal position, such restoration of the hand lever, returning the operable member or trip link 38, actuating lever 40, catch 55 and dog 43 to normal.

40 It is desirable that the operator be relieved from the necessity of manually operating the line spacing mechanism to turn the platen 2094 and feed the paper forward to the next line.

45 Therefore, as a convenient means for automatically effecting line spacing, during the return of the carriage to the beginning of a line, I provide a feed pawl 69 (Fig. 1) pivoted at 70 to a supporting bell crank 71, one arm of which is pivoted at 72 to the left hand end frame 2010 of the carriage. A spring 73 connected to a rearward extension on the feed pawl 69 and to a limit stud 74 mounted on the depending arm of the 50 supporting bell crank 71 and passing through a slot 75 in the feed pawl, tends to advance the tooth of the pawl towards a line space ratchet 76 at the left hand end of the platen 2094, the ratchet 76 being 60 adapted to turn with the platen.

The lower arm of the feed pawl 69 is formed with a cam 77, the low face of which normally lies against a control post 78 projecting laterally from the adjacent end plate 65 2010.

A headed guide stud 79 passes through a slot 80 in the supporting bell crank 71, to limit the rocking of the latter. The bell crank also carries a horn 81 preferably equipped with a roller 82 extending over 70 and adapted to ride along the upper carriage rail 2067^m. When, in traveling in column spacing direction, the left hand end of the carriage passes the left hand end of the carriage rail 2067^m, the roll 82 rides off the 75 rail, and the supporting bell crank lever 71 with its feed pawl 69 drops to its lowest position, in which it is held by the contact of the upper end wall of the slot 80 with the stud 79, which locates the upper toothed end 80 of the feed pawl 69 somewhat below the horizontal center of the line space ratchet 76 preparatory to taking a new bite on the ratchet. The spring 73 draws the tooth of the pawl towards the ratchet until the pawl 85 is arrested by contact of the inner end wall of its slot 75 with the post 74. The feed pawl 69, in dropping to its lower position, shifts the high face of its cam 77 below the control stud 78 against which the low face 90 of the cam is pressed by the spring 73, to enable this movement of the feed pawl to effective position.

The carriage, upon its return towards the beginning of a line, causes the roll 82 to 95 ride up an inclined face 83 formed on the end of the upper carriage rail 2067^m to rock the supporting bell crank 71 upwardly, the pawl 69 being carried therewith and entering its tooth in the overhanging teeth of the 100 ratchet 2094.

As the roll 82 rides up the incline 83, it raises the feed pawl 69 to force the ratchet 76 around one or more steps, and thus feed the paper in line spacing direction, and just 105 as the roll reaches the upper end of the incline, the high face of the cam 77 on the pawl rides onto the control stud 78 to throw the feed pawl 69 out of engagement with the ratchet, against the tension of the spring 110 73, the stud 74 traversing the slot 75 to its outer or rear end where it remains until the roll 82 again rides off the rail 2067^m.

Operation of the machine to accumulate and print an amount set up on the key- 115 board at a time when the carriage is being restored towards the beginning of a line, would blur the imprint and locate it out of line with previously printed amounts of a similar character, to prevent the possibility 120 of which, I provide an interlock between the starting key 966^b (Fig. 8) and the operable member or link 38.

To this end, I provide the lever 50 with a laterally projecting lug 84 located adjacent the arm 916^b (shown and described in U. S. patent to Wilgus 1,150,916, August 24, 1915, where it is given reference numeral 50) fast on the shaft 900^d (referred to as 27 in the above-mentioned patent) and 130

forming a part of the usual Wales construction.

A lateral ear 85 on the arm 916^b normally lies just in front of the lug 84.

5 Depression of the starting key 966^b rocks cross shaft 900^d counter-clockwise to introduce the ear 85 beneath the lever 50, and thereby block the operation of either lever 50 or 53 controlling the operating member 10 or trip link 38, while the starting key remains depressed.

Rocking either lever 50 or 53 will interpose the lug 84 in the path of the ear 85 to lock the starting key out of operation.

15 The releasable connection between the actuating lever 40 and the control shaft 32, as well as the automatic or carriage-controlled release mechanism for such connection, is more particularly covered in a separate application, filed November 2, 1920, Serial No. 421,332.

Changes may be made in the form and arrangement of the several parts without departing from the spirit and scope of this

25 invention.

What I claim as new, is—

1. The combination with a traveling paper carriage, and a motor having a shaft; of mechanism to return the carriage towards the beginning of a line, including a carriage-return shaft; separable drive and driven members mounted directly upon the motor shaft and carriage-return shafts, respectively, against axial travel relatively thereto, the separable members being normally disengaged to permit the carriage-return mechanism to remain at rest; and means to positively engage and disengage the separable members.

40 2. The combination with a traveling paper carriage, and a motor having a shaft; of mechanism to return the carriage towards the beginning of a line, including a carriage-return shaft; separable drive and driven members mounted directly upon the motor shaft and carriage-return shafts, respectively, against axial travel relatively thereto, the separable members being normally disengaged to permit the carriage-return mechanism to remain at rest; a shiftable bearing by which the carriage-return shaft is supported for lateral movement; and means to shift the bearing in opposite directions to engage and disengage the separable members.

45 3. The combination with a traveling paper carriage, and a motor having a shaft; of mechanism to return the carriage towards the beginning of a line, including a carriage-return shaft; a shiftable bearing in which one end of the carriage-return shaft is rotatably stepped; separable drive and driven members mounted on the motor shaft and on the carriage-return shaft, respectively; a

55 spring operable upon the shiftable bearing

to shift the latter and the carriage-return shaft in a direction to disengage the separable members, and normally hold them disengaged; and means operating upon the bearing to positively shift it and the carriage-return shaft in the opposite direction against the tension of the spring, to engage the separable members. 70

4. The combination with a traveling paper carriage; and a motor having a shaft; of mechanism to return the carriage towards the beginning of a line, including a carriage-return shaft extending at an angle to the motor shaft; a shiftable support in which one end of the carriage-return shaft is rotatably stepped; separable clutch members secured, respectively, to the motor shaft and carriage-return shaft; means to shift the support in a direction to disengage the separable members; a toe on the shiftable support; and a cam member operable upon the toe to positively shift the support in the opposite direction, to engage the separable members. 80 85

5. The combination with a traveling paper carriage; and a motor having a shaft; of mechanism to return the carriage towards the beginning of a line, including a carriage-return shaft; separable members, respectively connected with the motor shaft and the carriage-return shaft; means normally tending to maintain the separable members disengaged; an engaging element to positively enforce the engagement of the separable members against the influence of the disengaging means; operable means having a loose connection with the engaging element, to prevent direct control of the latter by the operable means to engage the separable members; drive means actuated by the operable means 105 to shift the engaging element to effective position; a catch to restrain the action of the drive means until such time as sufficient power is accumulated to operate the engaging element; and a trip means controlled by 110 the operable means to release the catch when the drive means is sufficiently powerful to operate the engaging element. 100

6. The combination with a traveling paper carriage; and a motor having a shaft; of mechanism to return the carriage towards the beginning of a line, including a carriage-return shaft; separable members, respectively connected with the motor shaft and the carriage-return shaft; means normally 115 tending to maintain the separable members disengaged; an engaging element to positively enforce the engagement of the separable members against the influence of the disengaging means; a drive means for the engaging element; a manually-operable means to store power in the drive means; a releasable catch to delay the operation of the drive means; and a trip member actuated by the manually-operable means to release the 120 125 130

catch and free the drive means for operation.

7. The combination with a traveling paper carriage; and a motor having a shaft; of mechanism to return the carriage towards the beginning of a line, including a carriage-

5 return shaft; separable members, respectively connected with the motor shaft and the carriage-return shaft; means tending to disengage the separable members; an en-
10 gaging element to positively enforce the engagement of the separable members; a drive means for the engaging element; an actuating lever connected with the engaging ele-
15 ment, and operated in one direction by the drive means to shift the engaging element to effective position; means manually-operable in opposite directions and having a limited movement relatively to the actuating lever, the manually-operable means, when shifted

20 in one direction, adapted to store power in the drive means; a releasable catch to retain the actuating lever in normal idle position; and a trip member actuated by the operable means to release the catch when the drive
25 means is sufficiently powerful to operate the actuating lever and engaging element.

8. The combination with a traveling paper carriage; and a motor having a shaft; of mechanism to return the carriage towards the beginning of a line, including a carriage-

30 return shaft; separable members, respectively connected with the motor shaft and the carriage-return shaft; means tending to disengage the separable members; an en-
35 gaging element to positively enforce the engagement of the separable members; drive means to shift the engaging element to effective position; operable means for the drive means, and having a limited movement relatively to the engaging element, to eliminate direct control of the engagement of the separable members by the operator; a releasable catch to prevent operation of the engaging element; and trip means controlled
45 by the operable means to release the catch.

9. The combination with a traveling paper carriage; and a motor having a shaft; of mechanism to return the carriage towards the beginning of a line including a carriage-

50 return shaft; separable members, respectively connected with the motor shaft and the carriage-return shaft; means tending to disengage the separable members; an en-
55 gaging element to positively enforce the engagement of the separable members; drive means to shift the engaging element to effective position; and means operable in one direction to actuate the drive means, and having a loose connection with the engaging element whereby to shift the latter to ineffective position when operated in the opposite direction.

10. The combination with a traveling paper carriage; and a motor having a shaft;

of mechanism to return the carriage towards the beginning of a line, including a carriage-return shaft; separable members, respectively connected with the motor shaft and the carriage-return shaft; means tending to disengage the separable members; an en-
70 gaging element to positively enforce the engagement of the separable members; drive means to shift the engaging element to effective position; means operable in one direction to actuate the drive means, and having a loose connection with the engaging element whereby to shift the latter to ineffective position when operated in the opposite direction; and carriage-controlled means to release the separable members to the action
75 of their disengaging means irrespective of the operable means.

11. The combination with a traveling paper carriage; and a motor having a shaft; of means to return the carriage towards the beginning of a line, including normally-separated drive and driven members; a normally idle engaging element to positively enforce the engagement of the separable members; an operable means having a limited movement relatively to the engaging element, to enable the engaging element to shift in one direction independently of the operable means; a catch to normally retain the engaging element in idle position; a drive means controlled by the operable means to shift the engaging element to effective position; and means also controlled by the operable means, to release the catch when sufficient power is stored in the drive means to actuate the engaging element.

12. The combination with a traveling paper carriage; and a motor having a shaft; of means to return the carriage towards the beginning of a line, including normally-separated drive and driven members; a normally idle engaging element to positively enforce the engagement of the separable members; an operable member having a limited movement relatively to the engaging element, to enable the engaging element to shift in one direction independently of the operable member; releasable means to normally retain the engaging element in idle position; drive means for the engaging element, such means interposed between the operable member and engaging element and controlled by the operable member; and means controlled by the operable member to trip the releasable retaining means when sufficient power is stored in the drive means to actuate the engaging element independently of the operable member.

13. The combination with a traveling paper carriage; and a motor having a shaft; of means to return the carriage towards the beginning of a line, including normally-sepa-

rated drive and driven members; a normally idle engaging element to positively enforce the engagement of the separable members; an operable member having a limited movement relatively to the engaging element, to enable the engaging element to shift in one direction independently of the operable member; releasable means to normally retain the engaging element in idle position; drive means for the engaging element, the power in which drive means is gradually increased by the actuation of the operable member in one direction; and means controlled by the operable member to trip the releasable retaining means when sufficient power is stored in the drive means, to actuate the engaging element independently of the operable member.

14. The combination with a traveling paper carriage; and a motor; of a drive mechanism between the motor and the carriage, including normally-separated drive and driven members; a normally idle engaging element to effect the engagement of the separable members; an actuating lever connected with the engaging element; a releasable catch to normally maintain the actuating lever and engaging element in idle position; a manually-operable member adapted to have a limited movement relatively to the actuating lever; a spring to act upon the actuating lever; the operable member adapted to store power in the spring, when shifted in one direction independently of the actuating lever; means controlled by the operable member, to release the catch subsequently to the storage of power in the spring, to enable the spring to shift the engaging element to effective position, the operable member adapted to restore the actuating lever and engaging element to idle position and return the catch to effective position, when shifted in the opposite direction; and means to automatically disconnect the separable members when the engaging element restores to idle position.

15. The combination with a traveling paper carriage; and a motor; of drive mechanism between the motor and carriage, including normally-separated drive and driven members; a normally idle engaging element to effect engagement of the separable members; releasable means normally effective to lock the engaging element in idle position; a manually-operable means, including a trip link adapted to have a limited movement relatively to the engaging element, to prevent direct control of the element by the trip link when the link is shifted in one direction; drive means for the engaging element; means operated by the trip link when shifted in one direction, independently of the engaging element, to release the locking means and thereby enable the drive means to

shift the engaging element to effective position; said trip link, when shifted in the opposite direction, adapted to return the engaging element to its normal idle position, and restore the releasable locking means to its effective position.

16. The combination with a traveling paper carriage; and a motor; of drive mechanism between the motor and carriage, including normally-separated drive and driven members; a normally idle engaging element to effect engagement of the separable members; manually-operable means shiftable in opposite directions, and having indirect control of the engaging element when shifted in one direction, and direct control of the engaging element when shifted in the opposite direction.

17. The combination with a traveling paper carriage; and a motor; of drive mechanism between the motor and carriage, including normally-separated drive and driven members; a normally idle engaging element to effect engagement of the separable members; manually-operable means shiftable in opposite directions, and having indirect control of the engaging element when shifted in one direction, and direct control of the element when shifted in the opposite direction; a drive means controlled by the manually-operable means, when shifted in one direction, to operate the engaging element to its effective position, the manually-operable means effective, when shifted in the opposite direction, to operate the engaging element to its ineffective position; and means to disengage the separable members when the engaging element is ineffective.

18. The combination with a traveling paper carriage; and a motor; of drive mechanism between the motor and carriage, including normally-separated drive and driven members; a normally idle engaging element to effect engagement of the separable members; manually-operable means shiftable in opposite directions, and having indirect control of the engaging element when shifted in one direction, and direct control of the engaging element when shifted in the opposite direction; a drive means controlled by the manually-operable means, when shifted in one direction, to operate the engaging element to its effective position, the manually-operable means effective, when shifted in the opposite direction, to operate the engaging element to its ineffective position; carriage-controlled means to shift the engaging element to its ineffective position; and means to disengage the separable members when the engaging element is ineffective.

19. The combination with a traveling paper carriage; and a motor; of drive

- mechanism between the motor and carriage, including normally-separated drive and driven members; a normally idle engaging element to effect engagement of the separable members; manually-operable means shiftable in opposite directions, and having indirect control of the engaging element when shifted in one direction, and direct control of the engaging element when shifted in the opposite direction; drive means to shift the engaging element to effective position; operable means adapted for movement relatively to the engaging element, to control the drive means; detaining means for the engaging element; and trip means actuated by the operable means to trip the detaining means and permit the drive means to shift the engaging element to effective position; the operable means adapted to shift the engaging element to ineffective position and restore the detaining means to effective position. 65
20. The combination with a traveling paper carriage; tabulating stops mounted thereon; an abutment with which the stops respectively contact, to arrest the carriage in various positions in its path of travel; means to draw the carriage in one direction; and a motor; of carriage-return mechanism between the motor and carriage, including normally-separated drive and driven members; a normally idle engaging element to effect the engagement of the separable members, manually-operable means shiftable in opposite directions, and having indirect control of the engaging element to shift the latter to effective position, whereby to engage the separable members and cause the drive mechanism to return the carriage towards the beginning of a line, the manually-operable means having direct control of the engaging element to disable the latter and interrupt the return of the carriage at any point in its return travel; and means to effect the separation of the separable members when the engaging element is disabled. 70
21. The combination with a traveling paper carriage; and a motor; of means to return the carriage to the beginning of a line, including separable members; means to disengage and hold the separable members normally separated; an engaging element to effect the connection of the separable members; a spring adapted to shift the engaging element to effective position; operable means to store power in the spring; detaining means to prevent the gradual operation of the engaging element; and means controlled by the operable means to trip the detaining means after the storage of power in the spring, the operable means adapted for movement relatively to the engaging element, to enable the operator to shift the engaging element to idle position, and free one of the separable members to the action of the disengaging means, to thereby interrupt the return travel of the carriage at any point in its path of return. 75
22. The combination with a traveling paper carriage; and a motor; of means to connect the motor and paper carriage to return the carriage towards the beginning of a line, including separable members; means to normally disengage the separable members; an engaging element to effect the connection of the clutch members; a drive means to shift the engaging element to effective position; operable means to store power in the drive means, and having a loose connection with the engaging element; the drive means normally adapted to take up the lost motion in the loose connection, to enable the operable means to shift the clutch-engaging element to ineffective position; a detaining means to delay the operation of the engaging element by its drive means; and trip means actuated by the operable means to release the detaining means. 80
23. The combination with a traveling paper carriage; and a motor; of means to connect the motor and paper carriage to return the carriage towards the beginning of a line, including separable members; means to normally disengage the separable members; an engaging element to effect the connection of the separable members; a drive means to shift the engaging element to effective position; operable means to store power in the drive means, and having a loose connection with the engaging element; the drive means normally adapted to take up the lost motion in the loose connection, to enable the operable means to shift the engaging element to ineffective position; a catch to delay the operation of the engaging element by its drive means; and a trip finger actuated by the operable means to release the catch. 85
24. The combination with a traveling paper carriage; and a motor; of means to connect the motor and carriage to return the carriage towards the beginning of a line, including normally idle separable members; means tending to disengage the separable members; an engaging element; drive means therefor; means operable in one direction to actuate the drive means, and in the opposite direction to shift the engaging element to ineffective position; a trip arm connected with the engaging element, and means on the carriage to contact the trip arm and shift the engaging element to ineffective position independently of the operable means. 90
25. The combination with a traveling paper carriage; and a motor; of means to connect the motor and carriage to return the carriage towards the beginning of a line, including normally idle separable members; means tending to disengage the separable

- members; an engaging element; drive means therefor; and means operable in one direction to actuate the drive means, and in the opposite direction to shift the engaging element to ineffective position.
26. The combination with a traveling paper carriage; and a motor; of means to connect the motor and paper carriage to return the paper carriage towards the beginning of a line, including normally idle separable members; means to disengage the separable members; an engaging element to effect the connection of the separable members; drive means therefor; means operable in one direction to actuate the drive means, and in the opposite direction to shift the engaging element to ineffective position; detaining means to delay the actuation of the engaging element by the operable means; trip means actuated by the operable means to release the detaining means; dual control means for the operable means, at least one of which permits the operator to restore the engaging means to ineffective position and interrupt the return travel of the carriage at any desired point; carriage feed means; tabulating stops; and an abutment with which the stops contact to arrest the carriage at any desired point in its travel.
27. The combination with a traveling paper carriage; and a motor; of means to connect the motor and paper carriage to return the paper carriage towards the beginning of a line, including normally idle separable members; means to disengage the separable members; an engaging element to effect the connection of the separable members; drive means therefor; means operable in one direction to actuate the drive means, and in the opposite direction to shift the engaging element to ineffective position; detaining means to delay the actuation of the engaging element by the operable means; trip means actuated by the operable means to release the detaining means; dual control means for the operable means, at least one of which permits the operator to restore the engaging means to ineffective position and interrupt the return travel of the carriage at any desired point; carriage feed means; tabulating stops; and an abutment with which the stops contact to arrest the carriage at any desired point in its travel; and carriage-controlled means to shift the engaging element to its ineffective position irrespective of the position of the operable means.
28. The combination with a traveling paper carriage; and a motor; of means to releasably connect the motor and carriage, to return the latter towards the beginning of a line, including normally-disconnected separable members; means to disengage the separable members; an engaging element; a drive means to shift the engaging element to effective position; an operable means to control the drive means, and having a loose connection with the engaging element to enable the operable means to shift the engaging element to ineffective position; a trip arm connected with the engaging element; and means on the carriage arranged to contact the arm and shift the engaging element to ineffective position as the carriage reaches the limit of its return travel.
29. In a calculating machine, having a main drive shaft; the combination with a motor; means to connect the motor and main drive shaft; a starting key to control the operation of such connection; and a traveling paper carriage; of carriage-return mechanism therefor, including normally-separated members; means, including an operable member, to cause the engagement of the normally-separated members; actuating means for the operable member; and interlocking means controlled by the starting key and the actuating means, respectively, to prevent concurrent action of the machine and of the carriage-return mechanism.
30. The combination with a traveling paper carriage; feed means to draw the carriage in one direction; and a motor; of means to restore the carriage to the beginning of a line against the influence of the feed means, the carriage-restoring means including normally idle separable members through which the motor is connected to the carriage; means to disengage the separable members; an engaging element to effect connection of the separable members; a link shiftable in opposite directions and adapted for movement relatively to the engaging element; a drive spring controlled by the link when shifted in one direction, to actuate the engaging element to effective position; a detaining means to delay the actuation of the engaging element; and a trip means controlled by the link to release the detaining means subsequently to the storage of power in the drive spring, the engaging element being shiftable by the link to its ineffective position at any point in the path of return of the carriage; a tabulating bar mounted in the carriage for endwise movement; means to limit the extent of such movement; tabulating stops on the bar; an abutment with which the stops contact to arrest the carriage in any desired position; and a cushioning device connected to the tabulating bar and to the carriage, respectively, to cushion the shock due to the contact of the stops with their abutment, when the return travel of the carriage is interrupted by the disconnection of the clutch members.
31. The combination with a traveling paper carriage, having a platen and a motor;

of means to releasably connect the motor and carriage to return the latter towards the beginning of a line; and line space mechanism for the platen, including a vibratory support; a line space pawl pivotally mounted thereon; a ratchet on the platen adapted for engagement by the pawl; a cam on the pawl; a control stud wiped by the

cam, as the pawl vibrates with its support, to disengage the pawl from its ratchet, and to enable the pawl to engage its ratchet; stationary inclined face; and means on the support adapted to ride upon the face as the carriage shifts in one direction or the other to vibrate the pawl support.

ARTHUR PENTECOST.
